GAME OF SKILL

Rudolf Peter and Heinz Bial, Vienna, Austria

Application March 11, 1938, Serial No. 195,324
In Austria March 18, 1937

1 Claim. (Cl. 273—138)

This invention relates to a game of skill of the coin-free type with automatic delivery of coins, in which provision is made and means provided to enable the player to effect mechanical setting of the apparatus to the various modes of playing the game of roulette (e. g. "black or red," "odd or even," etc.).

Two forms of construction embodying the invention are shown, by way of example, in the accompanying drawings, in which:

Figs. 1-7 show a form of construction in which a roulette ball is set in motion by the insertion of a coin or the like, Figs. 1 and 2 being a front elevation and a section, respectively, while

Figs. 3-5 show auxiliary or accessory contributions.

Fig. 6 shows a side elevation, partly in section, a roulette-wheel in the form of a cylinder, for use in the game according to the invention.

Fig. 7 shows the roulette-cylinder developed in a plane.

Figs. 8-10 show a simplified form of construction of the invention without the use of roulette balls.

Fig. 8 being an elevational view of the roulette-disc used in this form of the invention, while

Figs. 9 and 10 show in elevation and in section, respectively, the parts of the apparatus co-acting with the roulette-disc and the coin release.

In the front wall of the casing A there are several, for instance five, coin slots a^1-a^5 into which the coins are inserted according to the mode of playing decided on, e. g. into the slot a^1 to play "black or red," into the slot a^2 to play "odd or even", into the slot a^3 to play a single number, into the slot a^4 to play the first or second 18, and into the slot a^5 for playing "first, second, or third dozen." Adjoining these slots there are chutes b^1-b^5 . Opposite the open lower ends of these chutes there are disposed levers c^1-c^5 which are normally in the position shown in full lines (Fig. 3), and which are rocked by the descending coin into the position shown in broken lines. The coin then passes on to one or other of the runways d^1-d^5 (Figs. 1 and 2) leading to the coin container (Fig. 1) which is of conventional design.

For each mode of playing there is provided a separate ball d^1-d^5 , and each of these balls is situated in a compartment of a turnstile e^1-e^5 (Figs. 2 and 3) formed of two walls disposed at right angles to each other. In the normal position each of the turnstiles is arrested by a stop f^1-f^5 adapted to be released by the corresponding one of the lever arms c^1-c^5 rocked by a coin dropping down the corresponding one of the

chutes b^1-b^5 . For this purpose each of the lever arms c^1-c^5 is articulated to one of a set of vertical rods g^1-g^5 (Fig. 3) the lower ends of which form the corresponding tops f^1-f^5 . When one of the levers c^1-c^5 is rocked, on the descending of a coin, the corresponding rod g is moved upwards and the corresponding stop f releases the corresponding turnstile which is then rotated by the weight of the ball in the direction indicated by the arrow II (Fig. 3). The ball then enters the corresponding one of a set of shafts h^1-h^5 (Figs. 1-3) disposed beneath the turnstiles. Opposite the lower ends of these shafts are chambers i^1-i^5 disposed on a lever D pivoted at C (Figs. 4 and 5). This lever is capable of being rocked through 180° about the pivot point C by means of a knob E (Fig. 1) provided on the front wall of a casing A.

When the lever D is in the upper position which upper position is indicated in broken lines in Figs. 2 and 5 there adjoin the receiving chambers i^1-i^5 passages j^1-j^5 in which the corresponding ball is conducted to the roulette-wheel. The lever D coacts with a closing plate E' which, when the lever D is in the lower end position, is held by fixed stops G^1 and G^2 against the action of a spring F in such a position that it opens the chambers i^1-i^5 (Figs. 1 and 5), so that the roulette ball set in motion can run into the appropriate chamber. When the lever D is swung into the upper end position the stops G^1 and G^2 release the closing plate E'. This plate consequently bears in response to the action of the spring against the adjoining chambers i^1-i^5 , thereby preventing the ball present in one of the chambers from falling out. Shortly before the lever D reaches the upper end position the closing plate E' is so rocked relatively to the lever D by fixed stops H^1 and H^2 that the chambers i^1-i^5 are opened. Through one of the passages j^1-j^5 the ball then passes to the roulette-wheel.

The roulette-wheel consists, in the constructional example shown in Figs. 1-7, of a hollow cylinder I the transparent end I^1 of which (Figs. 1 and 6) is provided at the edge with numerals "1"—"36" and "0", and are, as usual, distributed in black and red (Fig. 1).

The cylinder I is divided by partitions I^2-I^5 into five compartments J^1-J^5 (Figs. 2 and 6). In each of these sections J^1-J^5 of this cylinder there are provided holes K corresponding to the numerals "1"—"36" and "0", through which the ball can drop. The arrangement, as the development of the cylinder in one plane (Fig. 7) shows, is such that on the generatrices of the cylinder

corresponding to the numerals on the numeral disc I^1 a hole K is provided in each of the five cylinder sections. The roulette ball then passes through one of the passages j^1-j^5 (Figs. 2 and 6) into one of the five cylinder compartments J^1-J^5 . Adjoining the passages j^1-j^5 there are tubes l^1-l^5 which extend almost up to the inner surface of the cylinder I . These tubes are disposed that their outlet orifices lie opposite those holes in the roulette cylinder which are lowermost when the cylinder is considered as being at rest.

The actuation of the roulette-cylinder is effected through the intermediary of a cord L (Figs. 1, 2, 4, and 5) taken over rollers L' , the one end of which is attached to the pivot axle of the cylinder, while the other end is secured to a thrust piece M which is slidable along a semi-circular guide N . Attached to the thrust piece M is a coil spring O the other end of which is secured to a fixed point O' . In the position shown in full lines (Fig. 4) the spring O is relieved of tension. If the thrust member M is displaced in the direction indicated by the arrow (Fig. 4) along the guide N this member eventually reaches the upper end position indicated in broken lines, the spring O being thereby tensioned. The displacement of the thrust member M is effected by means of a two-armed lever P which is pivoted about P' , and of which the forward end P'' acting as a driver engages, in the normal position, in a recess M' in the guide. The carrier P''' of the lever P bears against the lever D . When this latter lever is rocked from its lower to its upper end position the lever P is taken along with it and pushes, with its forward end, the thrust member M on the circular guide N in front of it until this member reaches its upper end position. When the parts are in this position the lever P , as indicated in broken lines in Fig. 4, encounters a fixed stop or abutment, e. g. the side wall of the casing, and is consequently rocked so that the driver P'' releases the thrust member M which then immediately returns along the guide N into the lower end position under the action of the spring O which has in the meantime become tensioned. The cord L attached to the thrust member M is thereby pulled and the roulette-cylinder set in rapid rotation.

The roulette-cylinder runs on of its own momentum after the spring O has reached the lower end position. For the purpose of applying a braking action to the cylinder there is provided a spring Q operable from the outside by means of a press-button or of a lever, so that the player is able to influence the length of time for which the cylinder runs and consequently is able to influence the result of the game. If the cylinder should happen to come to a standstill in such a position that there is no hole at the point where the tubes l^1-l^5 discharge the roulette ball would simply strike up against the cylinder wall and could not be conveyed further. To prevent this from happening the spring Q is so constructed that it brushes against the periphery of the cylinder and acts so as to cause the cylinder to come to a standstill invariably in such a position that the appropriate holes K are exactly opposite the conduits l^1-l^5 , so that the ball is certain to escape through one of the holes.

The setting of the apparatus to the selected mode of playing is effected by means of the dials n^1-n^5 (Fig. 1) provided on the front wall of the casing. Corresponding to the significance of the

five coin slots a^1-a^5 , the dial n^1 has two settings ("black" and "red"), the dial n^2 likewise two settings ("odd" and "even"), the dial n^3 as many settings as there are individual numbers playable, the dial n^4 two settings (for the first and second "18"), and the dial n^5 three settings (for the three dozens). The setting dials are severally connected with a set of ratchet discs o^1-o^5 (Fig. 3) which coact with a corresponding set of pawls p^1-p^5 . Each of these pawls extends with its outer end through a slot into the corresponding one of the shafts h^1-h^5 , so that the ball, on dropping through the shaft, encounters the appropriate pawl and releases the corresponding ratchet disc. The dial for the mode of playing selected by the player can then be operated. Rotation of any one of the setting dials shifts the appropriate one of the set of vertically guided rods q^1-q^5 (Fig. 3) which are severally operated by the ratchet discs o^1-o^5 through the intermediary of eccentrics r^1-r^5 . To the upper end of each of the rods q^1-q^5 there is articulated a bell-crank lever s^1-s^5 (Fig. 3) having a longitudinal slot s' . In each of these longitudinal slots s' there engages a horizontally guided rod t to the free end of which there adjoins a hose-pipe u^1-u^5 . Each of these hose-pipes discharges into the corresponding one of the chutes k^1-k^5 leading to the turnstiles e^1-e^5 . When one of the setting dials is operated the upper end of the corresponding one of the connecting hose-pipes u^1-u^5 is shifted through the intermediary action of the rods c and t . Beneath the roulette-cylinder (Figs. 2 and 6) there is a set of catching funnels v^1-v^5 adjoining which there are conduits w^1-w^5 which likewise discharge into the chutes k^1-k^5 above the corresponding turnstiles e^1-e^5 . Thus irrespective of whether the upper end of one of the hose-pipes u^1-u^5 is situated opposite the corresponding lowermost hole in the roulette-cylinder through which the ball drops, or not, the ball is able to find its way to the appropriate turnstile by travelling either through one of the hose-pipes u^1-u^5 or through one of the funnels v^1-v^5 and one of the conduits w^1-w^5 .

The mode of operation of the device is as follows:

It is assumed that the player wishes to play "black or red". He therefore inserts the coin in the slot a^1 . The coin rolls down the chute b^1 , drops on to the lever c^1 thereby releasing the turnstile e^1 which is then rotated by the weight of the ball which proceeds to drop through the chute h^1 into the catching chamber i^1 . On its way to the catching chamber the ball deflects the pawl p^1 extending into a slot in the chute h^1 , with the result that the setting dial n^1 is released. If the player decides to play "red" he first sets the dial n^1 to "red". This has the effect of bringing the hose-pipe u^1 into a position beneath the roulette cylinder at which there are holes corresponding to the red numbers.

After operation of the setting dial the knob E is rotated, which causes the lever D to be rocked into the upper end position. This rocking movement of the lever D brings about the following four results:

- (1) Locking of the setting dial, in that by means of a lever p' articulated to each pawl the pawl is returned into the locking position.
- (2) The chambers i^1-i^5 are closed, in that the closing plate E' is moved out of the path of the stops G^1 and G^2 and brought by the spring F into the position of closure.

(3) Shortly before the lever D reaches its upper end position the chambers i^1 — i^5 are opened again in the described manner, so that these chambers come opposite the passages j^1 — j^5 and the ball can enter the latter.

(4) The roulette-cylinder I is set in rotation in the already described manner.

In the meantime the ball is conducted through one of the passages j^1 — j^5 , in the present instance through the passage j^1 , and the chute k^1 up to the inner surface of the cylinder where it remains, unable to pass through one of the holes K, as long as the cylinder is in rotation. As soon, however, as the roulette-cylinder comes to a standstill in response to the braking action of the spring Q influenced at will by the player there will be a hole at the lowermost point of the cylinder. There are then two possibilities: if the hole in question corresponds to a "red" number (which the player wishes to play) then the ball passes into the hose-pipe u^1 appropriately positioned by the setting of the dial n^1 to "red". If on the other hand the hole is one corresponding to a "black" number the ball drops into the funnel v^1 . In either case the ball passes into the connecting conduit k^1 and thence again on to the turnstile e^1 .

Thus when the ball rolls into the hose-pipe u^1 the player has won, and the coins must then be delivered automatically. This is effected by causing the ball, after dropping down the hose-pipe u^1 to displace a lever X (Fig. 3) which extends with a pawl X' into a slot in the chute E¹, and which is displaced by the weight of the falling ball. The coin discharge lever X liberates, in a manner known in coin-freed devices, a Maltese cross Y which then liberates the appropriate number of coins from the coin container B. In the meantime the lever D returns in response to the action of the spring Z (Figs. 1, 3 and 4) into its initial position.

If the player plays a single number (coin inserted into slot a^3 , and operation of setting dial n^3) the corresponding ball runs into the front compartment of the roulette-cylinder, and the player sees the ball drop out through the chute i^3 which may if desired be made transparent. If the player decides on any other mode of playing the ball passes into a corresponding rear compartment of the roulette-cylinder, and the player would not therefore see the ball at all. It is however conducive to the attractiveness of the game, and enables the player to follow better what is happening, if the player can see the ball running whatever mode of playing is selected. This result can be achieved in a simple manner by causing each of the levers c^1 , c^2 , c^4 and c^5 by means of suitable transmission elements, e. g. the linkage z indicated in Fig. 2 to coact with the lever c^3 , whereby the ball allotted to the foremost compartment of the roulette-cylinder is liberated. In this manner whenever any one of the levers c^1 , c^2 , c^4 and c^5 is rocked by the dropping coin and the corresponding turnstile e^1 , e^2 , e^4 or e^5 liberated the turnstile e^3 is also at the same time released, so that invariably two balls come down, namely the one allotted to the foremost compartment of the cylinder, which is visible to the player as it runs, and the ball corresponding to the mode of playing selected. The holes K in the periphery of the cylinder are so distributed in the individual sections thereof that the same numbers appear on the same generatrices, so that the front ball always passes through a hole corresponding to the same number in all the compartments and

therefore also to the hole through which the actually played ball passes.

Referring now to the constructional example shown in Figs. 8 to 10, in place of the roulette-cylinder, is a roulette disc R having the numbers 1 to 36 and zero inscribed on alternately coloured sectors and mounted in the front wall of a casing (not shown) similarly to casing A in Figure 1. As in the previous embodiment, a number of coin slots a^1 , a^2 . . . are provided in the front surface or wall of such casing, adjoining each of which there is a chute. Of these coin-chutes only one chute i is shown (Fig. 9) of which it is assumed that it leads to a slot provided for use when playing a single number. Into the chute i there extends one end of a lever 3 articulated at 2 and retained by a spring 4 in the position shown in full lines. On the other end of the lever 3 there is a lug 5 which coacts with a further lever 8 stressed by a spring 7, articulated at 6, and bearing against a pin 9.

The coin coming down the chute i strikes against the lever 3 thereby rocking the latter into the position indicated in broken lines and then falls on down into the coin container (not shown in the drawings). As soon as the lever 3 is rocked the lug 5 liberates the lever 8 which, however, remains in its position as long as it rests upon the pin 9. Only after the pin 9 has been moved out of the path of the lever 8, in a manner to be described in due course, is such lever liberated and rocked by the spring 7 into the position indicated in broken lines.

Beneath the lever 8 there is provided a shiftable rod 10 the lower end of which coacts with a pawl 12, stressed by a spring 11, for the Maltese cross 13 of the coin delivering mechanism 14. When the lever 8 moves from the position shown in full lines into that indicated in broken lines it presses against the upper end of the rod 10, shifts this latter downwards, and thereby causes the pawl 12 to be rocked against the action of the spring 11, with the result that the Maltese cross 13 is liberated and coins delivered.

For playing a single number there is used a setting indicator knob (Fig. 10) the spindle of which is coupled by leverage 16 with a setting lever 18 pivoted about the pin 17. The pin 17 is so designed that when the setting indicating knob 15 is operated the lever 18 can be rocked in a plane parallel to the roulette-disc (i. e. in the direction indicated by the double arrow III in Fig. 9) while being additionally capable, in a manner to be described in due course, of receiving a supplementary pivotal movement and of slight extent in a direction at right angles to the plane of the roulette-disc.

The perforated-disc R has a central circular surface R^1 over which the holes 23 corresponding to the individual numerals "1"—"36" and "0" are distributed according to a certain plan. The holes in this circular area are intended for playing an individual number. Adjoining the circular area R^1 are four concentric annular rings R^2 — R^5 which correspond to the other modes of playing referred to in connection with the constructional example shown in Figs. 1-7 of the drawings. In each of these annular rings there is provided a complete set of holes a few only of which are indicated in the drawings, for the sake of simplicity.

The setting lever 18 can be so adjusted that its free end is approximately in the centre of the roulette-disc when in the one end position and reaches out to the periphery of the circular area

R^1 in the other end position. On the side facing the surface of the roulette-disc, the lever 18 is furnished with a pin 21 and is so pressed against the roulette-disc by a cam 19 that the pin 21 brushes against the disc. If, after the playing of a certain number, the lever 18 occupies a certain position, and the roulette disc, after the running mechanism has come to a standstill, is in such a position that the pin 21 is opposite a hole 23 , then the pin 21 is forced into the hole concerned, by the action of the cam 19 . To the lever 18 there is attached an arm 22 on the lower end of which there is provided a stud 8 acting as a stop for the lever 8 . The arm 22 is so connected with the setting lever 18 that this lever 18 is rockable independently of the arm 22 when the setting knob 16 is rotated, so that the arm 22 does not alter its position and the stop 8 therefore continues to retain the lever 8 in the locking position, but is carried along when the pin 21 enters one of the holes 23 (whereby the lever 18 is rocked slightly in a direction at right angles to the roulette-disc), so that the stop 8 is moved out of the path of the lever 8 , and thus frees this latter to release the coin discharging mechanism.

The above described contrivance operates as follows: The player sets the knob 16 to the selected numeral, with the result that the lever 18 is also correspondingly rocked. The coin is then inserted, with the result that in the above described manner the releasing mechanism for the coin discharge device is put in readiness for operation. The roulette-disc is then set in rotation, and there will be two possibilities, namely (1) the roulette-disc comes to rest in such a position that none of the holes 23 comes opposite the pin 21 . In this case the lever 18 undergoes no supplementary rocking towards the roulette-disc, the arm 22 and with it the stop 8 remain unaltered as to position, the lever 8 remaining blocked, the releasing means for the coin discharge device are not brought into action, and the player has lost; (2) the roulette-disc comes to a standstill in such a position that the pin 21 is opposite one of the holes 23 ; in this case the pin 21 is forced into the hole in question, and the stop 8 moved out of the path of the lever 8 in the described manner, so that this lever is completely freed, acts upon the coin discharging means to liberate the coins.

The lever 18 is returned into the initial position by a restoring spring 20 (Fig. 3), so that the pin 21 comes out of engagement with the hole 23 , and the arm 22 is also restored into a vertical position. Immediately before this rod 18 is forced upwards again by the spring 11 and takes the lever 8 along with it to become thereby rocked back again into the normal position in which it is fixed by the stop 8 , so that all the parts reassume their initial positions and are in readiness for the next cycle of play.

The described means for releasing the money

discharging mechanism and the setting lever co-acting with these means are provided in five sets, one for each mode of playing. There are thus five coin slots each with a vertical coin chute 5 with each of which a releasing device for the coin discharging mechanism coacts. There are likewise five setting dials for selecting the mode of playing. Each of these dials coacts with one of a set of adjusting levers 18 , and each of these 10 adjusting levers has a range of movement which is coextensive with the width of the appropriate one of the annular rings R^2 — R^5 of the roulette-disc R . Each of these sets of mechanism is exactly the same as that described for playing a 15 single number.

In this example the releasing of the coin discharge mechanism is effected by the provision in the roulette disc of holes into which the pin 21 on the adjusting lever 18 drops thereby actuating the stop (Fig. 9). Alternatively, instead of the holes 23 in the roulette-disc there may be provided contacts with which the pin 21 or a suitable part of the adjustable lever 18 is able to come in contact and thereby to close a current circuit comprising a relay or the like adapted to effect the releasing operation of the stop 8 .

We claim:

Coin freed apparatus comprising in combination a casing, a first visible rotary disc with differently coloured areas corresponding to the numbers 1 to 36 and zero similarly to a roulette wheel mounted in the front surface of the casing, a second disc coupled to the first disc, perforations in the second disc corresponding to the numbers 1 to 36 and secondary holes therein each corresponding to a group of such numbers, means released by the insertion of a coin for driving both discs and for braking their rotary movement after a pre-determined duration of rotation, 30 an index mounted visibly upon the first disc adapted to indicate a selected area of the disc when the latter is at rest, a plurality of manually operated rotary knobs serving as selectors movable in relation to the second disc and mounted 35 in the front surface of the casing, one knob at least permitting the selection of a group of numerals (black, red, even, odd), a setting lever positively connected to each knob, each setting lever being adapted to move parallel to the plane of the perforated disc and also at right angles thereto, a pin carried by each setting lever which at the vertical movement aforesaid enters one of the holes in the perforated disc, an eccentric member in engagement with each setting lever 40 for vertically displacing same relatively to the perforated disc when the latter is at rest, the holes in said disc being so distributed that the pin of the setting lever can enter one hole when the selected number corresponds with that indicated by the index after the visible disc has come to rest.

RUDOLF PETER.
HEINZ BIAL.
